Lewis J. Doolittle

ATTORNEY.

UNITED STATES PATENT OFFICE.

CHARLES B. LATENDORF, OF BAYONNE, NEW JERSEY.

CLAMP.

1,375,849.

Specification of Letters Patent. Patented Apr. 26, 1921.

Application filed June 12, 1920. Serial No. 388,534.

To all whom it may concern:

Be it known that I, CHARLES B. LATENDORF, a citizen of the United States, residing at Bayonne, Hudson county, New Jersey, have 5 invented certain new and useful Improvements in Clamps, of which the following is a specification.

This invention relates to a clamping device adapted particularly for use in theatrical work in connection with the supporting or placing of the scenes and is known as a cyclorama clamp used to support the back and side drops or scenes on the stage.

The object of the invention is to provide 15 a simple device for this purpose which avoids the necessity of boring holes in the supports or tying with ropes, etc., which is now resorted to as a means for supporting the arms carrying the scenes from the back 20 support, known as a batten.

In carrying out the invention I provide a clamping device composed of two main parts, one adapted to be attached in any position to the batten and the other, which is 25 hinged to the first by a hinge connection which permits movement in any direction and to any position, which carries the side arm. The attachment of the clamp to the batten and the attachment of the side arm 30 to its clamping member is accomplished without making any holes in the batten or side arm and also provides for the adjustment in position of the device on the batten and the changing of the side arm in a 35 simple manner, which will be explained and will appear more fully hereinafter in connection with the description of the device illustrated in the accompanying drawings.

In the drawings like parts in the several 40 views have been given the same reference numerals.

Figure 1 is a side view in elevation of the device, parts being shown in section to illustrate the construction.

45 Fig. 2 is a top plan view of the device as shown in Fig. 1.

The main clamp member is indicated at 1 and is constructed in the form of a box 50 without ends or bottom and of inverted U shape in cross section. Two extensions 2 and 3 are formed on one of the side walls of the main clamp member 1 to which a hinge is attached. This hinge is composed of a ball shaped member 4, which is provided 55 with two extensions or pins 5 and 6 projecting from opposite sides thereof and fit in

two holes, one in each of the projecting arms 2 and 3 on the main clamp 1.

The hole on the upper projection 2 is formed with one side beveled upwardly and 60 inwardly toward the body of the main clamp member 1, as shown at 7 in Fig. 1, and the pin 5 at this side of the ball 4 is longer than the pin 6 on the opposite side. The purpose of this construction is to permit 65 the hinge to be readily placed in position without removing the pins 5-6, which can be made in one piece with the ball 4. The arms 2 and 3 are spaced apart to allow the pin 5 to first be slipped into the hole in the 70 upper arm 2 in an angular position and then swung in to bring the pin 6 over its hole in the arm 3 and then dropped into position with the ball resting on the arm 3. A cotter pin 8 may then be placed in the pin 5 75 just below the arm 2 to prevent accidental displacement of the hinge.

The second member or arm clamp is indicated at 9 and is of box shape without one end or top. This member carries the side 80 arm which supports the side scene. At the end of this arm clamp are two projections 10 and 11, similar to the projections 2 and 3 on the main clamp 1, except that they are on the end instead of the side of the 85 clamp member. These arms 10 and 11 are spaced apart so that the hinge ball member 4 may be slipped between the same and a pin 12 passed through a hole in the ball 4 and holes in the arms 10 and 11. This pin 90 12 is then riveted over or otherwise secured to the arms 10 and 11.

Screw threaded holes 13 and 14 are provided on one side and similar holes 15 and 16 on the other side wall of the arm clamp 95 9 by means of which the scene arm may be secured thereto by set screws, which are used on one side only to permit the arm to swing against the main support 1 and the batten.

A similar set screw may be used in the 100 main clamp 1 at 17 to secure the same to the batten in any position.

What I claim is:—

1. A device of the class described, comprising two clamp members and a ball member provided with projecting pins engaging in openings in extensions from said clamp members, one of said openings being formed with one side beveled upwardly and inwardly toward the body of the clamp to permit the ball member and pin to be slipped into the opening in an angular position and 105 110

swung into a vertical position to allow the second pin to be engaged in its opening.

2. A device of the class described, comprising a box shaped clamp member of inverted **U** shape adapted to be secured to the batten, a second clamp member of similar shape adapted to support a scene arm, said first named clamp member being provided with extensions from one side thereof and said second clamp member being provided with extensions from one end thereof, a hinge member composed of a ball shaped

member positioned between said extensions, a pin passing through said ball member and one of said clamp members, projections from said ball member engaging in openings in the other of said clamp members, one of said openings being formed with one side beveled upwardly and inwardly to permit the insertion of said hinge member in position. 15 20

In testimony whereof, CHARLES B. LATENDORF has signed his name to this specification, this 16th day of April, 1920.

CHAS. B. LATENDORF.
